UNITED STATES PATENT OFFICE.

FRANK J. REICHMANN, OF CHICAGO, ILLINOIS.

AMPLIFYING HORN.

Application filed June 25, 1923. Serial No. 647,614.

To all whom it may concern:

Be it known that I, FRANK J. REICHMANN, citizen of the United States, residing at Chicago, in the county of Cook and State of Illinois, have invented certain new and useful Improvements in an Amplifying Horn; and I do hereby declare the following to be a full, clear, and exact description of the invention, such as will enable others skilled in the art to which it appertains to make and use the same.

My invention relates to amplifying horns particularly suitable for use in connection with radio-receiving apparatus, loud speaking telephone receivers, phonographs and the like for amplifying the emitted sounds and projecting them in a predetermined general direction. Amplifying horns for such purposes have long been employed in connection with phonographs where the concealing of the horn permits it to be built of quite thick material, where no attention needs to be paid to an artistic appearance, and where an excessive weight of the horn is not objectionable since the horn is permanently supported within a strong cabinet. However, when amplifying horns are used in connection with radio receiving outfits, it is highly desirable that these should be sufficiently light so as to be readily portable and that they should be of artistic configurations. These new requirements bar the use of amplifying horns constructed after the general manner of those employed in modern phonographs.

So also, when amplifying horns are used for magnifying the reproduction of a spoken message, as in the case of loud speaking telephones employed for paging guests in hotels, a distortion of the tone qualities is immaterial as long as the enunciation is sufficiently clear to make the words understood. However, since wireless receiving outfits are used largely for receiving musical renditions, it is highly important that distortions of the tonal effects, either by an undue accentuation of tones of certain pitch ranges or otherwise, should be avoided. This requirement has not been met in the amplifying horns now in common use, since metal horns (unless so heavy as to lack the desired portability) will vibrate bodily in response to high notes, while wooden horns will do the same in response to notes of lower pitches, and in either case the accentuating of a certain range of notes will

distort the music which is being amplified by the horn. On the other hand, a horn made of a soft and sound-deadening material will absorb so much of the sound as to reduce the amplifying effect which is due to the shape of the horn, thereby annulling the advantages which such a horn would otherwise possess on account of its not accentuating tones of selected pitch ranges.

My invention aims to overcome the above mentioned objections to horns made of the heretofore customary materials by providing an amplifying horn made of sounds deadening and sound-vibratory material so intermingled and combined as to avoid any pitch accentuation (at least within the common range of voice and music transmission) without causing any considerable sound absorption. More particularly, it aims to provide amplifying horns made of a composition which has as one of its ingredients a material with air cells of such microscopic proportions that these air cells will have a sound-deadening effect to the desired extent when the said ingredient is distributed in finely divided form through a composition whose other ingredients are good sound transmitters. That is to say, it aims to provide a horn having in its composition so large a proportion of intimately intermingled cellular and air-filled particles as to reduce both the transverse sound transmission through the horn, and the bodily vibration of the latter, while still having a high sound-reflecting efficiency and while having the strength and elasticity required for enabling the horn to withstand rough handling. It also aims to provide a horn of this class which can readily be manufactured in highly artistic shapes and with any desired thickness of wall without employing a core, which will readily permit any surface irregularities or roughnesses due to defects in the manufacture to be corrected during the process of manufacture, which can readily be provided with surface coatings of any desired coloring both for the sake of appearance and for increasing the sound reflection, and which will be sufficiently light so as to be readily portable even when constructed in large sizes.

Furthermore, it aims to provide a horn which will have the additional desirable characteristics hereafter described. Illustrative of my invention, Fig. 1 is a perspective view showing one of the forms in which

the horn of my invention can readily be made, namely a form which is difficult to duplicate in most materials and particularly so in a thin walled form.

5 Fig. 2 is a central and vertical section through the same horn.

Fig. 3 is a greatly magnified transverse section of a wall portion of the horn, showing the general distribution of the constituent materials.

10 In accomplishing the purposes of my invention, I construct my horn of a composition formed of an inherently resonant and somewhat resilient binder intimately intermingled with a sound-deadening material. For the latter, I preferably employ a thin walled and cellular air-filled material in the form of infusorial earth ground to pass through a 150 or 200 mesh screen, desirably 15 securing this infusorial earth from a locality (such as California) in which the same can be obtained in a variety having the quite low specific gravity due to an unusually large air content. For the binder I desirably 20 employ a gelatinous type, such as a hide stock glue, and I render this resilient by a suitable admixture of other ingredients. After molding a horn from these ingredients properly proportioned to secure the above 25 described desirable acoustic effect, I desirably provide both the interior and the exterior surfaces of the horn with a suitable glossy and sound reflecting coating, such as a lacquer of any desired color.

30 In manufacturing my amplifying horn, I may thoroughly intermingle from sixty to sixty-five parts by weight of finely ground infusorial earth with a liquid solution composed of about forty parts of ground glue, 35 eighty to one hundred parts of water, and about ten parts each of commercial glycerin and of a socalled non-drying oil. This mixture when well intermingled at a temperature of about 150° F. is poured into a suitable 40 shaped mold, such as the mold 1 of Fig. 2, the mold being plugged at the bottom and held in such a position that the liquid mixture entirely fills the same. The mold itself can readily be made of ordinary plaster of 45 Paris from a model corresponding in general shape to the exterior of the desired horn but having its linear dimensions about one-seventh greater than those of the proposed finished horn, so as to allow for the shrinkage. If made of plaster of Paris, the interior 50 of the mold is first coated with a film for preventing the resulting solid composition from adhering to the mold, for which purpose I may employ a mixture of one part 55 of stearic acid with about three parts of kerosene.

The liquid mixture as poured into the mold is left in the same for a sufficient length of time to permit the outer portion thereof to 60 congeal against the surface of the mold in a

desired thickness, after which the plug or plugs of the mold are removed so as to draw off the uncongealed liquid rapidly and desirably in directions away from the mouth of the horn. If the layer of solid material 70 thus formed is insufficient for the desired thickness of the horn, I can increase the thickness by adding one or more additional layers. For example, I may allow the initial layer to cool within the mold for about a 75 minute, or to an extent insufficient for loosening it from the mold. I then fill the bore of the initial layer with diluted formalin and allow this to stand for about ten minutes, during which time the formaldehyde 80 which forms the active constituent of the formalin renders the glue adjacent to the inner surface of the thin molded horn insoluble, thereby preventing the initial layer from being dissolved by liquid mixture introduced afterwards for forming the next layer. I then draw off the formalin solution and allow the thin-molded horn to stand within the mold for ten or fifteen minutes, thereby permitting the excess of formalin to evaporate from its inner surface, after which I proceed as before by pouring a new quantity of the liquid mixture into the mold and thereby depositing a second layer inside the first. The same general procedure can be continued for forming a third layer if desired, although I have found that with the composition proportioned as above described for affording the desired acoustic properties, I can readily produce horns of 100 ample strength in large commercial sizes with only two layers. After the horn has been molded to the desired thickness, it is allowed to cool within the mold sufficiently so that it can readily be removed without tearing it and it can then be dried further on suitable supports after being withdrawn from the mold.

The amplifying horn as thus produced has decided advantages over one made from the 110 previously employed compositions from an acoustic standpoint, as I have found by my experiments that it is unusually effective in delivering the amplified tone at its mouth and in avoiding an interference with the amplified tones by a resonant vibration of the horn itself. While I have not entirely determined the reasons for this superiority, the following explanation seems to be in accordance with recent investigations on sound 115 transussions.

In amplifying sound while also guiding it from its smaller end to its mouth, the horn effects the amplification by the reflection of sound within its bore, this bore being of a size gradually increasing in a desirably logarithmical proportion. At the same time, the material of the horn acts as a partition between the sound passing through the horn and the outer air, so that 120

the general principles involved in the transmission of sound through partitions should apply to an amplifying horn as effecting its efficiency. Investigations on the sound-proofing of partitions have shown that air-filled materials do not vibrate as readily as entirely solid materials, and that the transmission of air through partitions is greatly reduced if the sound waves have to pass successively through quite different substances. In my composition, one of the main ingredients is infusorial earth, also known as diatomaceous earth or kieselguhr, a mineral which is noted for its microscopic cellular structure, and its fine grained consistency. This material, even when ground to pass through a screen of 150 to 200 mesh (in which grade of fineness I desirably use it) still shows air cells under the microscope, or in other words, each such fine particle of it has air confined in a large number of cells within it. Hence, a sound wave in passing through such a particle is modified when passing from a wall of the cell to the air within it and this wave is modified again when passing from the confined air to the opposite cell wall. Moreover, the cell walls themselves are quite thin and of low sound conductivity so that their poor conducting of sound cooperates with the modification of the sound waves when changing from cell walls to air (and vice versa) in making the infusorial earth a good sound deadening material.

If the horn were made entirely of this ingredient, it would unduly absorb and dampen the sound, but such an effect is offset by the inherent resonance and sound-reflecting quality of the binder employed for making a solid composition with the infusorial earth as its main body portion. That is to say, by suitably proportioning and intimately combining such a material of high sound-deadening characteristics with a binder which by itself would be a good sound conductor and resonator, I produce a horn which is neither decidedly resonant nor sound-absorbing and which might be designated as neutral in these respects. That is to say, I produce a horn which will not readily vibrate as a unit and which therefore will avoid the undesirable accentuating of some one portion of the range of tones which are being amplified.

The considerable air content together with the low specific gravity of the cell walls of the infusorial earth also reduce the specific gravity of the finished composition, so that my amplifying horn is relatively quite light and readily portable. So also, by employing a binder which affords a high reflecting surface, I secure the desired sound reflection within the horn and I can readily increase this by the inner coating of lacquer or the like after the manner shown in Fig. 3. By starting with finely ground infusorial earth and thoroughly intermingling this with the dissolved glue, I secure a composition of quite uniform texture and by having a suitable proportion of a resiliency imparting ingredient mixed with the glue, I secure that toughness in the horn which will prevent it from cracking or chipping even if roughly handled, while the vibration-deadening effect of the air fillings of the cellular infusorial earth prevent this resiliency from imparting an undesirable resonance to the horn. Moreover, by employing such proportions of the ingredients as those above recited, I can produce amplifying horns of quite large sizes and ample strength with unusually thin walls.

With an amplifying horn thus produced, the layers blend integrally into each other, so that the division between the first layer 2 and the second layer 3 (as indicated by the dotted line 5 in the magnified section of Fig. 3) cannot be discerned, and a relatively thin inner coating 4 of lacquer is ample. Thanks to the flexibility which such a horn possesses when only partly dried, it can readily be removed from such a mold as that shown in Fig. 2 without even withdrawing the air vent plug 6 or the drainage plug 7 which may be employed to facilitate the use of such a mold.

However, while I have mentioned desirable ingredients in proportions which I have found highly practical, I do not wish to be limited to these or to the manufacturing methods above recited, it being obvious that many substitutions and variations might be made without departing either from the spirit of my invention or from the appended claims. Neither do I wish to be limited to the use of my novel amplifying horn in connection with sound reproducing devices.

I claim as my invention:

1. A sound amplifying horn made entirely of a molded composition having a highly cellular mineral sound deadening material as its preponderant ingredient and having a substantially uniform wall thickness throughout its length.
2. A sound amplifying horn having its main wall portion made of a solid and uniform composition whose chief ingredients are a highly cellular sound deadening material and a binder penetrating the cells of the aforesaid material.
3. A sound amplifying horn having a relatively thin walled body made of a solid composition comprising a sound deadening material and a sound-vibratory binder combined in finely divided and intimately intermingled form and in such proportions as to make the resulting horn neither integrally sound-vibratory nor sound-deadening.
4. A sound amplifying horn having a rel-

- 4
- atively thin walled body made entirely of a molded composition, the said composition consisting mainly of finely ground mineral material whose particles are highly cellular, and of a smaller proportion of a resonant binder.
5. A sound amplifying horn made of a composition consisting mainly of a finely ground mineral cellular material and a binder, and having a substantially uniform wall thickness throughout.
6. A sound amplifying horn made of a composition consisting mainly of infusorial earth and a gelatinous binder.
- 10 7. A sound amplifying horn made of a composition consisting mainly of finely ground infusorial earth intermingled with a smaller amount by weight of a gelatinous binder.
8. A sound amplifying horn composed mainly of finely ground infusorial earth, intermingled with a smaller amount by weight of a gelatinous binder and of an ingredient for enhancing the resiliency of the gelatinous binder.
- 15 9. A sound amplifying horn composed mainly of finely divided infusorial earth intimately intermingled with the gelatinous binder and having a relatively thin coating of a sound reflecting material on its interior surface.
- 10 10. A sound amplifying horn comprising a hollow body made of a solid composition whose chief ingredients are a finely divided sound deadening material intimately intermingled with a sound reflecting material, and a relatively thin coating of a different sound reflecting material extending throughout the bore of the said hollow horn body.
- 15 11. A sound amplifying horn made of a solid composition whose chief ingredients are finely ground infusorial earth intimately intermingled with a binder, the proportions of the infusorial earth and the binder being such that the inherent resonance of the binder is largely offset by the sound-deadening property of the infusorial earth.

Signed at Chicago, Illinois, June 21st, 1923.

FRANK J. REICHMANN.
